14 Claims. (Cl. 260—313)

This invention is concerned with specific bis-imino-pyrrolines as new compositions of matter. It also deals with a method for the preparation of these bis-imino-pyrrolines.

The compounds of this invention are prepared by reacting a cyanoketone having the formula

with a diprimary amine having the formula

in a molecular ratio of substantially two of the former to one of the latter, to be more fully explained hereinafter. The bis-iminopyrrolines produced may be represented by the formula

Actually, the compound represented by Formula I is, in varying degrees depending principally on reaction conditions and the values of A, R₁, R₂, R₃, and R₄, in tautomeric relationship with the compounds having the following structures

It is believed that the predominant tautomeric product is that represented by Formula I but appreciable amounts of II, III, and IV are undoubtedly present, based on the best experimental and analytical evidence. In the present instance, Formula I will be referred to as the most probable form of the four possible tautomeric structures (I, II, III, and IV), but such reference is meant to include all four of the tautomeric forms.

The symbol R₁ represents hydrocarbon groups of one to ten carbon atoms, preferably alkyl, aralkyl, cycloalkyl, aryl, and alkaryl. The symbol R₂ represents a

hydrogen atom or an alkyl group of one to four carbon atoms. The symbols R₃ and R₄ may be hydrogen atoms or hydrocarbon groups containing from one to ten carbon atoms including alkyl, aralkyl, cycloalkyl, aryl, and alkaryl groups. In addition, R₁ and R₂ taken together with the carbon atoms to which they are joined may form a carbocyclic ring containing five to six carbon atoms which in turn may have alkyl substituents containing a total of no more than four additional carbon atoms. In addition, R₂ and R₃ taken together with the carbon atoms to which they are joined may form a carbocyclic ring containing five to six carbon atoms which in turn may have alkyl substituents containing a total of no more than four additional carbon atoms. In addition, R₃ and R₄ taken together with the carbon atoms to which they are joined may form a carbocyclic ring containing five to six carbon atoms which in turn may have alkyl substituents containing a total of no more than four additional carbon atoms. The total number of carbon atoms in the cyanoketone should not exceed twenty-four. The preferred embodiments are those in which R₁ and R₄ are alkyl groups, R₂ is a hydrogen atom, and R₃ is a methyl group. R₁, R₃, and R₄ may typically individually represent methyl, butyl, octyl, benzyl, phenylbutyl, cyclopentyl, cyclohexyl, phenyl, naphthyl, butylphenyl groups, and the like.

Typical cyanoketone reactants include

- 4-oxopentanone, 30
 3-methyl-4-oxopentanone, 3-methyl-4-oxopentanone, 30
 2,2-dimethyl-4-oxopentanone, 2,2-dimethyl-4-oxopentanone, 30
 2-methyl-2-ethyl-4-oxopentanone, 2-methyl-2-ethyl-4-oxopentanone, 30
 2,4,8-trimethyl-4-cyano-6-nanone, 2,4,8-trimethyl-4-cyano-6-nanone, 30
 2-methyl-2-ethyl-4-oxopentanone, 2-methyl-2-ethyl-4-oxopentanone, 30
 2-methyl-2-ethyl-4-oxoheptanone, 2-methyl-2-ethyl-4-oxoheptanone, 30
 2-isobutyl-2,6-dimethyl-4-oxoheptanone, 2-isobutyl-2,6-dimethyl-4-oxoheptanone, 30
 2-methyl-2-neopentyl-4-oxopentanone, 2-methyl-2-neopentyl-4-oxopentanone, 30
 2-methyl-2,4-diphenyl-4-oxobutanone, 2-methyl-2,4-diphenyl-4-oxobutanone, 30
 2-(1-cyanocyclohexyl)-cyclohexanone, 2-(1-cyanocyclohexyl)-cyclohexanone, 30
 2-methyl-2,4-dicyclohexyl-4-oxobutanone, 2-methyl-2,4-dicyclohexyl-4-oxobutanone, 30
 5-methyl-2-(1-methyl-1-cyanoethyl)-cyclohexanone, 5-methyl-2-(1-methyl-1-cyanoethyl)-cyclohexanone, 30
 1,3,3-trimethyl-5-oxocyclohexane-carbonitrile, 1,3,3-trimethyl-5-oxocyclohexane-carbonitrile, 30
 2-acetyl-1-methylcyclopentanecarbonitrile, 2-acetyl-1-methylcyclopentanecarbonitrile, 30
 1-butyl-2-methyl-3-oxocyclopentanecarbonitrile, 1-(2-oxocyclopentyl)-cyclohexanecarbonitrile, 30
 1-(1-pentyl-2-oxooctyl)-cyclohexanecarbonitrile, 1-(1-pentyl-2-oxooctyl)-cyclohexanecarbonitrile, 30
 1-octyl-2-methyl-3-oxocyclohexanecarbonitrile, 1-octyl-2-methyl-3-oxocyclohexanecarbonitrile, 30
 3,3-dimethyl-2-(2-oxopropyl)-bicyclo[2.2.1]heptane-2-carbonitrile, 3,3-dimethyl-2-(2-oxopropyl)-bicyclo[2.2.1]heptane-2-carbonitrile, 30
 2-benzoyl-1-methylcyclopentanecarbonitrile, and 2-benzoyl-1-methylcyclopentanecarbonitrile, 30
 2-butyl-2-naphthyl-4-oxobutanone, and 2-butyl-2-naphthyl-4-oxobutanone.

The symbol A represents a chain, cyclic or acyclic, of at least four carbon atoms, A is usually hydrocarbon in content but may very well include a secondary or tertiary amino group, an ether oxygen atom, a thioether sulfur atom, and the like. While the upper limit of carbon atoms in A is not especially critical about 24 is considered the practical upper limit. In addition to the carbon atoms there may be one or more nitrogen, oxygen, or sulfur atoms present as previously mentioned. With regard to the reactant NH₂-A-NH₂ it is necessary that there be at least four carbon atoms between the two primary amino groups. It is also necessary that each of the primary amino groups be attached to a carbon atom that in turn is attached to no more than two carbon atoms. In other words, the carbon atom to which each of the primary amino groups is attached must bear at least one hydrogen atom, otherwise the reaction is not consummated probably because of interfering steric conditions.

acetonitrile give N,N'-bis - (3,3,6 - trimethyl - 2,3,4,5,6,7 - hexahydroindol - 2 - ylidene) - p - phenylenediamine.

Example 2

Diethylenetriamine (72 parts), 2,2-dimethyl - 4 - oxopentanotriple (125 parts), and benzene (40 parts) are charged to a reactor fitted with a water separator and capped by a reflux condenser. The reaction mixture is boiled under reflux and water is separated azeotropically. When the theoretical amount of water (18 parts) separates, the material is stripped under reduced pressure and finally to 90° C. at 0.1 mm. absolute pressure.

Calculated for $C_{18}H_{31}N_6$: total nitrogen—22.0%; titratable nitrogen—13.2%. Found: total nitrogen—21.2%; titratable nitrogen—12.1%.

The product is 1,7-bis(2,4,4 - trimethyl-2-pyrrolin-5-ylidene)-1,4,7-triazaheptane and has the following structure

In a similar fashion 1,5,8,12-tetrazadodecane and 2,2-dimethyl - 4 - oxopentanotriple give 1,12-bis(2,4,4-trimethyl - 2 - pyrrolin - 5 - ylidene) - 1,5,8,12 - tetrazadodecane; 1,9 - diaza - 5 - oxanonane and 1-(2-oxocyclohexyl) - cyclohexanecarbonitrile give 1,9 - bis(3,3-pentamethylene - 2,3,4,5,6,7 - hexahydroindol - 2 - ylidene) - 1,9 - diaza - 5 - oxanonane; 1,9 - diaminodiaza - 5 - thianonane and 2 - acetyl - cyclohexanecarbonitrile give 1,9 - bis(3 - methyl - 2,4,5,6,7,7a - hexahydroisoindol - 1 - ylidene) - 1,9 - diaza - 5 - thianonane; and 1,15 - diaza-8-oxapentadecane and 3-methyl-4-oxapentanotriple give 1,15-bis(2,3-dimethyl - 2 - pyrrolin - 5 - ylidene) - 1,15-diaza-8-oxapentadecane.

Example 3

Xylene (30 parts), 1,10-diaminodecane (17.2 parts), and 2-methyl - 2,4 - diphenyl - 4 - oxobutanotriple (50 parts) are refluxed for twenty-four hours until the theoretical amount of water (3.6 parts) separates. The reaction mixture is stripped under reduced pressure to give the product 1,12 - bis(4 - methyl - 2,4 - diphenyl - 2 - pyrrolin-5-ylidene)-1,12-diazaheptane, in high yield. In a similar fashion there are prepared N,N'-bis(3,3-pentamethylene - 2,3,4,5,6,7 - hexahydroindol - 2 - ylidene)-2,5 - diaminobicyclo(2.2.1)heptane from 1 - (2-oxocyclohexyl) - cyclohexanecarbonitrile and 2,5-diaminobicyclo(2.2.1)heptane; N,N' - bis(4 - methyl - 2,4 - dihexyl - 2 - pyrrolin - 5 - ylidene) - 1,4-di(aminomethyl) - cyclohexane from 1,4-di(aminomethyl)-cyclohexane and 2 - methyl-2-hexyl-4-oxodecanotriple; and 1,10-bis(2,4,4-trimethyl - 2 - pyrrolin - 5 - ylidene) - 1,4,7,10 - tetrazaheptane from triethylenetetramine and 2,2-dimethyl - 4 - oxopentanotriple.

We claim:

1. A member from the group consisting of the compound whose principal tautomeric form is represented by the formula

and the pharmaceutically acceptable acid addition salts thereof, in which A represents a member of 4 to 24 carbon atoms from the group consisting of alkylene, cycloalkylene, phenylene, alkylene - phenylenealkylene, alkylenealkyl substituted phenylenealkylene, phenylenealkylene, alkylenealkylenealkylene, bicycloalkylene, and an alkylene interrupted by at least one member of the class consisting of an amino group, an alkylamino group,

an ether oxygen atom, and a thioether sulfur atom, provided that there are at least 2 carbon atoms between the members of said class, R₁ taken individually represents a member from the class consisting of alkyl, phenylalkyl, cycloalkyl, phenyl, naphthyl, and alkylphenyl groups of no more than 10 carbon atoms, R₂ taken individually represents a member from the class consisting of a hydrogen atom and an alkyl group of 1 to 4 carbon atoms, R₃ and R₄ taken individually represent members from the class consisting of alkyl, cycloalkyl, phenylalkyl, phenyl, naphthyl, and alkylphenyl groups of no more than 10 carbon atoms, R₁ and R₂ taken collectively with the carbon atoms to which they are joined form a member from the class consisting of a carbocyclic ring of 5 to 6 carbon atoms and one olefinic bond, and said ring having alkyl substituents consisting of a total of no more than 4 carbon atoms, R₂ and R₃ taken collectively with the carbon atoms to which they are joined from a member from the class consisting of a saturated carbocyclic ring of 5 to 6 carbon atoms and said ring having alkyl substituents consisting of a total of no more than 4 carbon atoms, and R₃ and R₄ taken collectively with the carbon atoms to which they are joined from a member from the class consisting of a saturated carbocyclic ring of 5 to 6 carbon atoms and said ring having alkyl substituents consisting of a total of no more than 4 carbon atoms.

2. The compound whose principal tautomeric form is represented by the formula

35 in which A represents an alkylene chain of 4 to 24 carbon atoms, R₁ is an alkyl group of 1 to 10 carbon atoms, R₂ is a hydrogen atom, R₃ is an alkyl group of 1 to 10 carbon atoms and R₄ is an alkyl group of 1 to 10 carbon atoms.

40 3. The compound whose principal tautomeric form is represented by the formula

in which A represents an alkylene chain of 4 to 24 carbon atoms, R₁ and R₄ are alkyl groups of 1 to 10 carbon atoms, R₂ is a hydrogen atom, and R₃ is a methyl group.

45 4. The compound whose principal tautomeric form is represented by the formula

55 in which A represents an alkylene chain of 4 to 24 carbon atoms, R₁ and R₂ taken collectively with the carbon atoms to which they are joined represent a carbocyclic ring of 5 to 6 carbon atoms having one olefinic bond and R₃ and R₄ are alkyl groups of 1 to 10 carbon atoms.

60 5. The compound whose principal tautomeric form is represented by the formula

65 in which A represents an alkylene chain of 4 to 24 carbon atoms, R₁ is an alkyl group of 1 to 10 carbon atoms, R₂ and R₃ taken collectively with the carbon atoms to

which they are joined form a saturated carbocyclic ring of 5 to 6 carbon atoms and R_4 is an alkyl group of 1 to 10 carbon atoms.

6. The compound whose principal tautomeric form is represented by the formula

in which A represents an alkylene chain of 4 to 24 carbon atoms, R_1 is an alkyl group of 1 to 10 carbon atoms, R_2 is an alkyl group of 1 to 4 carbon atoms and R_3 and R_4 taken collectively with the carbon atoms to which they are joined form a saturated carbocyclic ring of 5 to 6 carbon atoms.

7. As a composition of matter, 1,8-bis(2,4,4-trimethyl-2-pyrrolin-5-ylidene)-1,8-diazaoctane.

8. As a composition of matter, 1,8-bis(2,4-dimethyl-4-neopentyl-2-pyrrolin-5-ylidene)-1,8-diazaoctane.

9. As a composition of matter, 1,7-bis(3,3-penta-methylene-2,3,4,5,6,7-hexahydroindol-2-ylidene)-1,4,7-tri-azaheptane.

10. As a composition of matter, 1,7-bis(2,4,4-trimethyl-2-pyrrolin-5-ylidene)-1,4,7-triazaheptane.

11. As a composition of matter, 1,12-bis(2,4,4-trimethyl-1-yl-2-pyrrolin-5-ylidene)-1,5,8,12-tetraazadodecane.

12. A method for the preparation of a compound having the formula

in which A represents a member of 4 to 24 carbon atoms from the group consisting of alkylene, cycloalkylene, phenylene, alkylenephenylenealkylene, alkylenealkyl substituted phenylenealkylene, phenylenealkylene, alkylene-cycloalkylenealkylene, bicycloalkylene, and an alkylene interrupted by at least one member of the class consisting of an amino group, an alkylamino group, and an ether oxygen atom, and a thioether sulfur atom, provided that there are at least 2 carbon atoms between the members of said class, R₁ taken individually represents a member from the class consisting of alkyl, phenylalkyl, cycloalkyl, phenyl, naphthyl, and alkylphenyl groups of no more than 10 carbon atoms, R₂ taken individually represents a member from the class consisting of a hydrogen

atom and an alkyl group of 1 to 4 carbon atoms, R_3 and R_4 taken individually represent members from the class consisting of alkyl, cycloalkyl, phenylalkyl, phenyl, naphthyl, and alkylphenyl groups of no more than 10

- 5 carbon atoms, R_1 and R_2 taken collectively with the carbon atoms to which they are joined form a member from the class consisting of a carbocyclic ring of 5 to 6 carbon atoms and one olefinic bond, and said ring having alkyl substituents consisting of a total of no more than 4 carbon atoms, R_2 and R_3 taken collectively with the carbon atoms to which they are joined form a member from the class consisting of a saturated carbocyclic ring of 5 to 6 carbon atoms and said ring having alkyl substituents consisting of a total of no more than 4 carbon atoms, and R_3 and R_4 taken collectively with the carbon atoms to which they are joined form a member from the class consisting of a saturated carbocyclic ring of 5 to 6 carbon atoms and said ring having alkyl substituents consisting of a total of no more than 4 carbon atoms, which comprises reacting at temperatures from 40° to 250° C., a compound having the formula

with one having the formula

30 in which there are at least 4 carbon atoms between the two primary amino groups and in which each of the primary amino groups is attached to a carbon atom that bears at least one hydrogen atom.

13. A method according to claim 12 in which the reaction is conducted in the presence of an inert volatile organic solvent that forms an azeotrope with water.

14. A method according to claim 12 in which the reaction is conducted in the presence of an inert organic volatile solvent that forms an azeotrope with water and the water formed in the reaction is removed azeotropically as the reaction progresses.
